UNITED STATES PATENT OFFICE.

GEORGE WALKER KELLEY AND ISAIAH S. KELLEY, OF NEW YORK, N. Y.

RAILROAD SANITARY APPARATUS.

1,138,486.

Specification of Letters Patent.

Patented May 4, 1915.

Application filed June 19, 1914. Serial No. 846,090.

To all whom it may concern:

Be it known that we, GEORGE W. KELLEY, a citizen of the United States, and a resident of the city of New York, borough of Bronx, 5 in the county and State of New York, and ISAIAH S. KELLEY, a citizen of the United States, and a resident of the city of New York, borough of Manhattan, in the county of Bronx and State of New York, have invented a new and Improved Railroad Sanitary Apparatus, of which the following is 10 a full, clear, and exact description.

Among the principal objects which the present invention has in view are: To provide impounding means for railway toilets, 15 adapted to be emptied by authorized persons; to provide means for heating the impounding receptacle to prevent freezing of the contents thereof; to provide a steam-heating equipment for said receptacle, having an automatic drain to prevent the accumulation of water therein; and to simplify the construction and the means for operating the same.

25 Drawings: Figure 1 is a vertical side view of a sanitary apparatus constructed and arranged in accordance with the present invention; Fig. 2 is a vertical section taken as on the line 2—2 in Fig. 1; Fig. 3 is a vertical section taken as on the line 3—3 in Fig. 1, showing the impounding receptacle in 30 closed relation; Fig. 4 is a vertical section taken on the same plane as provided for Fig. 3, the receptacle being shown as in its open 35 or dumping position.

Description: As seen in the drawings, the fixture 9 is provided with a waste-pipe 10 extending through the floor structure of a car. The fixture and pipe may be provided 40 with any suitable valve pan. At the lower end, the pipe 10 is provided with an inclination, to form with a reinforcing collar 11 a closure seat. The inclination of the seat thus provided is such as to permit the 45 swinging receptacle to firmly rest thereon when in service position, such as shown best in Fig. 3 of the drawings, and to swing therefrom to assume the position as shown best in Fig. 4 of the drawings.

50 Pivots mounted on trunnions 12 and

13, in bearings formed in the ends of pendant brackets 14, is a metal case 15.

The case 15 is provided with a pipe section 16 of larger diameter than the waste-pipe 10, and is provided with a reinforcing 55 collar edge 17 to seat against the reinforcing collar 11 of said waste-pipe.

As shown best in Figs. 3 and 4 of the drawings, the metal case 15 is preferably constructed of separable sections, said sections being provided with bolting flanges 18 and 19. The upper half of the case is preferably permanently united with, or integrally formed with, the trunnions 12 and 13, the lower half of the casing to be held firmly 60 and in position by means of bolts 20. If it becomes necessary to pack, or otherwise render the joint steam-tight, between the bolting flanges 18 and 19 and the joint between the lower half of the case 15 and said trunnions, this may be accomplished, employing 65 for that purpose any suitable and conventional method. The construction also provides for the ready and convenient removal 70 of the container 21 when desired.

75 The container 21 is constructed of any suitable material, such as enamel metal, or porcelain or other vitreous material. As shown in Figs. 4 and 5, the container has a short neck to extend within the pipe section 80 16, the upper edge of said neck being protected by the upper end of the pipe section 16, so as to present no edges to operate as a lodgment. The container 21 is supported in the metal case 15 in such a manner as to 85 provide a channel or space 22 surrounding the body of said container. When the bolts 20 are tightened, the container 21 is held firmly in the metal case 15, to avoid rattling 90 of or injury to said container. The mounting thus provided to prevent the rattling of the container also prevents the dislodgment thereof when the container is inverted to be dumped, as shown best in Fig. 4 of the drawings. The inversion of the container 95 and case illustrated in Fig. 4 is accomplished by rotating the metal case 15 on its trunnions 12 and 13. To provide for this action, a sprocket wheel 23 is rigidly mounted on the trunnion 12 within a 100

guard case 24. Operatively connecting the sprocket wheel 23 and a second sprocket wheel 25 is a sprocket chain 26. Intermediate the two sprocket wheels, and suitably mounted within the lower extension of the case 24, are idler pulleys 27, shown best in Fig. 2 of the drawings. The sprocket wheel 25 is mounted on a short spindle 28, the outer end whereof is provided with a 5 squared wrench section 29, suitably located in the passageway of a car, or other suitable location outside of the room in which the fixture 9 is placed, and in position to be at all times and under all conditions accessible to the brakeman or other authorized person upon whom devolves the duty of dumping the impounding receptacle. The dumping is now accomplished by the brakeman or other authorized person first releasing 10 the bolt 30 and then applying a suitable wrench to the section 29, with which to turn the spindle 28 and wheel 25 mounted thereon. It will be understood that this operation is to be performed irrespective of the 15 condition of use of the fixture 9, it being understood that regulations provide for the dumping of the receptacle at certain places in the roadway. After overturning and emptying the container 21, the operator 20 swings the case 15 back to service position, and removes the wrench or key from the section 29, and tightens the bolt 30, to hold rigidly thereafter the case 15 and container 21 in service position.

35 Steam is admitted to the space 22 through a pipe 31 when a controlling valve 32 is opened. The pipe 31 has a nipple 33, which extends through a gland packing 34, in the 40 trunnion 13, which is bored to form a pocket for said packing, and a passage for said nipple, as shown best in Fig. 1 of the drawings. The steam thus admitted to the space 22 prevents the freezing of the contents of 45 the container 21, as might occur in exceedingly cold weather, due to the exposed position of the case 15. When using the steam, however, provision is to be made for the condensation within the space 22, and this 50 is accommodated by providing a sump or well 35. The bottom of the well 35 is perforated to form a delivery passage 36. Surrounding the inner end of the passage 36, a seat for the ball valve 37 is formed. The 55 valve 37 is constructed to be floated by water when collected in the well 35. When the valve 37 is floated, the water in the well 35 escapes therefrom by way of the passage 36, and re-seats the valve to permit the further accumulation of water in the well.

Claims:

1. An apparatus as characterized, comprising a toilet fixture having a pendent waste-pipe; a rotary container having a receiving pipe section to register in service 65

with said waste-pipe, forming a continuous passage between said fixture and said container; means for rotating said container; and a casing for said container, infolding the same in spaced relation thereto, to provide a heating chamber therefor. 70

2. An apparatus as characterized, comprising a toilet fixture having a pendent waste-pipe; a rotary container having a receiving pipe section to register in service 75 with said waste-pipe, forming a continuous passage between said fixture and said container; means for rotating said container; a casing for said container, infolding the same in spaced relation thereto to provide 80 a heating chamber therefor; and means for supplying a heating medium to said chamber.

3. An apparatus as characterized, comprising a toilet fixture having a pendent waste-pipe; a rotary container having a receiving pipe section to register in service 85 with said waste-pipe, forming a continuous passage between said fixture and said container; a casing for said container, infolding the same in spaced relation thereto to provide 90 a heating chamber therefor; means for rotating said casing; and a steam-heating system arranged for supplying steam to said chamber. 95

4. An apparatus as characterized, comprising a toilet fixture having a pendent waste-pipe; a rotary container having a receiving pipe section to register in service 100 with said waste-pipe, forming a continuous passage between said fixture and said container; a casing for said container, infolding the same in spaced relation thereto to provide a heating chamber therefor; means for rotating said casing; a steam-heating system arranged for supplying steam to said 105 chamber; and means mounted on said casing for voiding liquid accumulation.

5. An apparatus as characterized, comprising a toilet fixture having a pendent waste-pipe; a rotary container having a receiving pipe section to register in service 110 with said waste-pipe, forming a continuous passage between said fixture and said container; a casing for said container; infolding the same in spaced relation thereto to provide a heating chamber therefor; means for rotating said casing; a steam-heating system arranged for supplying steam to said 115 chamber; and means mounted on said casing for voiding liquid accumulation, and embodying a floating valve arranged to be lifted from its seat by the accumulation of liquid in said casing. 120

6. An apparatus as characterized, comprising a toilet fixture having a pendent waste-pipe; a rotary container having a receiving pipe section to register in service 125 with said waste-pipe, forming a continuous passage between said fixture and said container; infolding the same in spaced relation thereto to provide a heating chamber therefor; means for rotating said casing; a steam-heating system arranged for supplying steam to said 130 chamber; and means mounted on said casing for voiding liquid accumulation.

tainer; means for rotating said container; and a casing for said container, infolding the same in spaced relation thereto, to provide a heating chamber therefor, said casing comprising separable sections, said sections being rigidly united in service relation.

5 In testimony whereof we have signed our

names to this specification in the presence of two subscribing witnesses.
